[57] CLAIM

The ornamental design for a portable two-way communication device, as shown and described.

DESCRIPTION

FIG. 1 is an isometric view of a portable two-way communication device showing our new design thereof;

FIG. 2 is a front side elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is an isometric view of a second embodiment of a portable two-way communication device showing an integral antenna;

FIG. 8 is a front side elevational view thereof;

FIG. 9 is a right side elevational view thereof;

FIG. 10 is a left side elevational view thereof;

FIG. 11 is a top plan view thereof; and,

FIG. 12 is a bottom plan view thereof.

The broken lines showing the antenna portion in FIGS. 1-5, as well as the broken lines shown throughout the views, are for illustrative purposes only and form no part of the claimed design.
